A. JONES.
DRAFT APPLIANCE FOR CHIMNEYS OR VENTILATOR STACKS.
APPLICATION FILED SEPT. 29, 1919.
1,345,195.

Patented June 29, 1920.

INVENTOR.
Alfred Jones,
BY *James O. Sherry*
his ATTORNEY.

UNITED STATES PATENT OFFICE.

ALFRED JONES, OF CHICAGO, ILLINOIS.

DRAFT APPLIANCE FOR CHIMNEYS OR VENTILATOR-STACKS.

1,345,195.

Specification of Letters Patent. Patented June 29, 1920.

Application filed September 29, 1919. Serial No. 327,267.

To all whom it may concern:

Be it known that I, ALFRED JONES, a citizen of the United States, and a resident of the city of Chicago, county of Cook, and 5 State of Illinois, have invented certain new and useful Improvements in Draft Appliances for Chimneys or Ventilator-Stacks, of which the following is a full, true, and exact description, reference being had to the 10 accompanying drawing, forming a part of this specification.

This invention relates to draft appliances for chimneys or ventilator stacks and its principal object is to increase the efficiency 15 of devices of this character. Another object is to provide improved means for positively directing currents of passing air upward around the smoke flue and over the top of the same, to thereby increase the 20 draft. The invention consists in the several novel features hereinafter fully set forth and claimed.

The invention is clearly illustrated in the accompanying drawing, in which—

25 Figure 1 is a perspective view of a draft appliance embodying a simple form of the present invention; Fig. 2 is a central, vertical section therethrough; Fig. 3 is a horizontal section taken on line 3—3 of Fig. 2; 30 Fig. 4 is a horizontal section taken on line 4—4 of Fig. 2, and Fig. 5 is a fragmental, vertical section taken on line 5—5 of Fig. 3.

Referring to said drawing, the reference character 6 designates a chimney of ordinary construction and 7 designates the draft appliance. The device is preferably constructed of upper and lower, separable sections 8, 9, the lower section 9 having a 35 rectangular base portion 10 surrounding 40 and resting upon the chimney top. The sides 11, of the lower section are flat, and incline upward toward the center of the device; at the upper end of the flat, inclined sides, is a tubular end or pipe 12.

45 Riveted or otherwise secured to the corners made by the inclined sides 11, are wings or webs 13 that extend, practically, from top to bottom of said corners, and said wings are formed with transverse flanges 50 14 along their outer edges. The wings 13 with their flanges, and the sides 11 form channels or troughs having overhanging edges (the flanges 14) which confine and direct upward any current of air caught between the wings 13. Conveniently, the wings 55

may be made of sheet metal, bent upon themselves as is clearly shown in Fig. 4 and they have base portions or webs 15 that fit around the corners and are riveted to the inclined sides 11.

60 The upper section 8 comprises a tubular stack 16 having upon its lower end an outwardly and downwardly flaring hood 17 that rests upon the wings 13 (see Fig. 5) and said wings may be tapered toward their 65 upper ends, as at 18, to fit against the inner face of the hood 17. The stack 16 is somewhat larger in diameter than the tubular end or pipe 12 of the lower section and it is spaced away therefrom by struts or other 70 spacers 19 preferably riveted or otherwise secured to the pipe 12. It is to be observed that an annular air passage 20 is left between inclined sides 11 and hood 17 which is continued upward between the pipe 12 and 75 stack 16, as at 20.

Above the stack 16 is supported a conical water shed 21 which may be secured to the stack 16 by metal strips 22. A band of metal 23 is fastened to the stack 16 near 80 its upper end and is formed with loops 24, to which guy wires may be secured for the purpose of steadyng the stack 16.

In operation, any current of air striking 85 any inclined side 11 is caught between the wings 13 at the edges of that side, and directed upward into the annular space 20 between the upper ends of the inclined side and hood 17, from which it passes up through the annular space 20^a and passes out through 90 the upper open end of the stack 16, producing an injector-like action and drawing the smoke or other gases up through the lower section 9, and discharging them out through the upper end of the stack 16. 95 The arrows *a*, in Fig. 2, indicate the passage, through the device, of a current of air, moving in a direction from right to left in Fig. 2, and the arrows *b* indicate the passage of smoke or other gases through the 100 device.

Obviously, the appliance may be secured upon the top of ventilator stacks and may be used for ventilating purposes, as is well understood.

105 More or less variation of the exact details of construction is possible without departing from the spirit of this invention; I desire, therefore, not to limit myself to the exact form of the construction shown and 110

described, but intend in the following claims to point out all of the invention described herein.

I claim as my invention:

- 5 1. A draft appliance, comprising a rectangular base portion having upwardly and inwardly inclined, flat sides, terminating in a tubular end, and wings secured to the sides at the corners thereof and formed with transverse flanges, said inclined sides, with their flanged wings, converging upwardly toward each other, and a stack spaced away from and surrounding said tubular end and having a downwardly and outwardly flaring hood resting upon and supported by said wings.
- 10 2. A draft appliance, comprising a rectangular base portion having upwardly inclined, flat sides, terminating in a tubular end, and wings secured thereto at the corners, and formed with transverse flanges, said inclined sides, with their flanged wings, converging upwardly toward each other,
- 15
- 20

and a removable stack surrounding and spaced away from said tubular end and 25 having a downwardly an outwardly flaring hood resting upon and supported by said wings, said inclined sides, wings and hood forming individual air passages, disposed around the upper end of the base portion. 30

3. A draft appliance, comprising upper and lower sections, the upper section comprising a stack having a downwardly and outwardly flaring hood at its lower end, and the lower section comprising a rectangular base formed with individual upwardly inclined trough-like members disposed around a common center and converging toward each other, the edges of said trough like members having transverse flanges extending to and under said hood and forming the support for said upper section, there being a tubular end at the top of the inclined trough-like members projecting up into said stack. 35

ALFRED JONES.
